(57)

CLAIM

The ornamental design for a package, as shown and described.

DESCRIPTION

FIG. 1 is a perspective view of a package in the open position showing our new design;

FIG. 2 is front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1, the bottom view being a mirror image thereof;

FIG. 7 is a front view of the design of FIG. 1 in the closed position;

FIG. 8 is a front view of a second embodiment of the design of FIG. 1 in the closed position and sealed with dot tape.

FIG. 9 is a perspective view of the design shown in FIG. 1 in a condition of use;

FIG. 10 is a front view of the design shown in FIG. 9, the rear view being identical to that of FIG. 3; and,

FIG. 11 is a left side view of the design shown in FIG. 9, the right side view being identical to that of FIG. 5.

The broken lines in FIGS. 9 through 11 represent unclaimed environmental subject matter included in order to show the package in a position of use.
